No. 896,074.

PATENTED AUG. 18, 1908.

J. AUBLE & C. GORDON.
EXPANSION ATTACHING PLATE FOR STEAM RADIATOR PIPES.
APPLICATION FILED JAN. 15, 1908.

UNITED STATES PATENT OFFICE

JOHN AUBLE AND CRAWFORD GORDON, OF NEW YORK, N. Y.

EXPANSION ATTACHING-PLATE FOR STEAM-RADIATOR PIPES.

No. 896,074.

Specification of Letters Patent.

Patented Aug. 18, 1908.

Application filed January 15, 1908. Serial No. 410,907.

To all whom it may concern:

Be it known that we, JOHN AUBLE and CRAWFORD GORDON, citizens of the United States, and residing at New York, in the county of New York and State of New York, have invented certain new and useful Improvements in Expansion Attaching-Plates for Steam-Radiator Pipes, of which the following is a specification, such as will enable 10 those skilled in the art to which it appertains to make and use the same.

This invention relates to steam radiators and particularly to the pipes for supplying steam thereto and returning the water of 15 condensation; and the object of the invention is to provide an improved attaching or base plate for the pipes of radiators of this class and which is attached to the base board of a room or compartment through which the 20 supply and return pipes are passed horizontally and which will permit of the expansion and contraction of said pipes without in any way interfering with the operation of the radiator or marring or otherwise injuring the 25 base board, and which will serve as an ornamental device of this class.

The invention is fully disclosed in the following specification, of which the accompanying drawing forms a part, in which the 30 separate parts of our improvement are designated by suitable reference characters in each of the views, and in which;—

Figure 1 is a side view of a steam radiator showing its connection and showing in section a part of the wall of a compartment or room and a base board secured thereto; Fig. 35 2 a front view of our improved expansion plate; Fig. 3 a section on the line 3—3 of Fig. 2; Fig. 4 a back view of the expansion 40 plate; and, Fig. 5 a transverse section on the line 5—5 of Fig. 2.

In the drawing forming part of this specification, we have shown at *a* an ordinary steam radiator, at *a*² a pipe for supplying 45 steam thereto and at *a*³ a pipe for conveying away the water of condensation. We have also shown at *b* a part of a wall of a room or compartment of a building and at *c* a base board secured to said wall. Arranged in or 50 back of the wall *b* is an upright steam supply pipe *d*, for supplying steam to radiators located in various rooms or compartments of the building, and at *d*² a pipe for returning or conveying away water of condensation.

55 The pipe *d* is connected with the radiator in

the usual manner by the pipe *a*², and the pipe *d*² is connected with the radiator in the usual manner by the pipe *a*³.

The pipes *a*² and *a*³ are passed through the base board *c* in the usual manner, said board being provided with a large opening *c*² for this purpose and, in the practice of our invention, we provide an expansion plate *e* which is secured to said base board and which comprises a back member *e*² and a 65 front member *e*³. The back member *e*² of our improved expansion plate is oblong in form and the corners thereof preferably rounded, and said back member is provided with a large central longitudinal opening *e*⁴ 70 and composed of two separate similar side portions *e*⁵, each of which is provided with holes or apertures *e*⁶ whereby the expansion plate may be secured to the base board *c* by means of screws, nails or otherwise. The 75 front member *e*³ of the expansion plate is of the same form as the back member *e*², but is of less dimensions, the dimensions thereof being greater than the dimensions of the opening *e*⁴ in the back member *e*², and said 80 front member is provided with a back-wardly directed flange *e*⁷ which bears on the back member and by which said members are separated.

The separate parts *e*⁵ of the back member 85 of the expansion plate are provided centrally of their inner edges with raised longitudinal lips *f* formed integrally therewith, and the front member *e*³ of said expansion plate is provided centrally of its opposite sides with 90 longitudinal keepers *f*² formed integrally therewith, and on the inner side thereof, and adapted to receive the lips *f* and, in practice, the separate parts of the expansion plate are connected by slipping the lips *f* of the parts 95 *e*⁵ of the back member *e*² into the keepers *f*² of the front member *e*³ and then securing the back member to the base board, and when the parts of the expansion plate are thus connected, the front member *e*³ will be free to 100 move vertically on the part *e*² within certain limits or enough to provide for the expansion and contraction of the pipes *a*² and *a*³.

The front member *e*³ of the expansion plate is provided with a top circular opening 105 *g* through which the pipe *a*² passes, and with a bottom opening *g*² through which the pipe *a*³ passes, and the vertical diameter of which is greater than the transverse diameter.

When the parts are connected up as shown 110

and described and steam turned on, the pipe d will be first heated after which the pipe a^2 will be heated, or these two pipes will be heated substantially at the same time, and 5 this will cause a greater or less vertical movement of the pipe a^2 , and this raises the front member e^3 of the expansion plate, but the opening g^2 through which the pipe a^3 passes is of such form as to permit this movement of 10 the front member e^3 of the expansion plate, and any other movement caused by the expansion and contraction of the parts d and a^2 and d^2 and a^3 may thus be accommodated in the expansion plate as will be readily understood. 15

By means of this construction the pipes a^2 and a^3 are held out of contact of the base board c , and said base board is given an attractive finish where said pipes pass there- 20 through and the danger of marring or otherwise injuring said base board is avoided, and the hole or aperture in said base board through which the pipes a^2 and a^3 pass is entirely concealed. 25

Having fully described our invention, what we claim as new and desire to secure by Letters Patent, is:—

1. An attaching or base plate device for the horizontally arranged supply and return 30 pipes of a steam radiator, comprising two plates, one of which is stationary and the other vertically movable thereon, the stationary plate being provided with a large oblong vertically arranged central opening, and 35 the movable plate being provided with two openings arranged in vertical line, the bot-

tom opening being oblong in form with the greater diameter thereof ranging vertically.

2. An attaching or base plate device for the horizontally arranged pipes of a steam 40 radiator, comprising an oblong back plate having a large oblong central opening, and a vertically movable front plate mounted thereon and provided with two vertically arranged openings, the vertical diameter of the 45 bottom opening being greater than the transverse diameter thereof.

3. An attaching or base plate device for the horizontally arranged supply and return pipes of a steam radiator, comprising an ob- 50 long back plate member provided with an oblong central opening, and a front plate member mounted thereon and adapted to close said opening and provided with two openings arranged in vertical line, the vertical diameter of the bottom opening being greater than the transverse diameter thereof, and said back plate member being divided longitudinally into two separate similar parts, and said parts being provided with 55 vertically arranged guides in which the front plate member is movable.

In testimony that we claim the foregoing as our invention we have signed our names in presence of the subscribing witnesses this 60 14th day of January 1908.

JOHN AUBLE.
CRAWFORD GORDON.
